UNITED STATES PATENT OFFICE

SYLVESTER W. KIRK, RICHARD J. BLUM, AND WILLIAM ROGER MEUTTMAN, OF CINCINNATI, OHIO, ASSIGNORS TO THE KIRK & BLUM MANUFACTURING COMPANY, OF CINCINNATI, OHIO, A CORPORATION OF OHIO

DUST COLLECTING SYSTEM

Application filed December 16, 1927. Serial No. 240,530.

This invention relates to a dust collecting system whereby miscellaneous waste and by-product materials of various weights are both gathered and conveyed and has for an object the provision of a simplified device for this purpose.

Another object is to provide a collecting system of the type referred to which is efficient and which operates with a minimum of power.

Another object of the invention is to provide a structure for the purposes stated which utilizes the force of gravity in effective gathering of waste material and by means of which the material thus gathered may be conveyed great distances entirely without the use of mechanical material moving conveyors and without loss of suction power.

A further object of the invention is to provide for auxiliary suction fans in such system and to further provide means whereby such auxiliary fans may be automatically controlled by varying conditions in the system.

These and other objects are attained by the means described herein and disclosed in the accompanying drawings, in which:

Fig. 1 is a side elevation of a device of the invention, part being broken away.

Fig. 2 is an end view of the device shown in Fig. 1.

Fig. 3 is a cross sectional view on line 3—3 of Fig. 1.

Fig. 4 is a plan view of a modified form of the device of the invention such as would be used in extremely long and extended installations.

Fig. 5 is a fragmental elevational view showing somewhat diagrammatically a mechanism for automatically varying the auxiliary power fans.

Fig. 6 is a fragmental view showing a modified form of speed regulator for auxiliary power fans in the device of this invention.

The device comprises a casing 7 which is conveniently formed of sheet metal substantially semi-circular in cross section. Secured beneath the semi-circular casing 7 are hoppers 8 having inclined sides 9. These hoppers are fashioned in the shape of inverted truncated pyramids having one pair of opposed top edges 10 secured to the depending edges of the casing member 7 and suitably reinforced by reinforcing strips 11 which may take the form of angle irons.

The opposed pair of top edges 12 are secured one each to similar edges of adjacent hoppers 8 so that the series of hoppers and the casing 7 together form a pipe. The opposite ends of the casing 7 are closed by substantially semi-circular plates or members 13. As shown in cross section in Fig. 1 each hopper terminates in a somewhat restricted port or opening 14 which communicates with the combined suction and conveyor pipe 15. The connection between the hopper and pipe 15 may be made directly if desired, but is preferably effected by a rectangular collar 16 which may extend perpendicularly between the pipe 15 and the hopper or it may be inclined to provide a continuous straight chute with an inclined wall 9 of the hopper as shown in Fig. 1. Suitable feeder pipe collars 17 are tapped into the casing 7 horizontally and from either or both sides of said casing. These collars 17 are cut into the casing at whatever points are found convenient in the layout of waste producing machines to which they connect by suitable feeder pipes 18 that convey the material. It will be apparent from the foregoing that the arrangement of the feeder pipes 18 is flexible and adapted to alteration without disturbing the main structure of the system. The alterations are readily effected by tapping in additional collars where needed and capping or closing such collars as are not required. Such arrangement is found ideal in shop layouts wherein the machinery arrangement is subject to frequent change because it practically eliminates the heretofore excessive cost of rearrangement and replacement of dust collecting system equipment.

In such installations as require pipes of great length it is found highly desirable to gradually reduce the diameter of the conveyor and suction pipe 15 as it extends away from the exhaust fan 19. By such arrangement it is possible to attain uniform suction through each port 14 regardless of its dis-

tance (within limits) from the fan. The suction and conveyor pipe 15 terminates closely adjacent the bottom opening in the hopper farthest from the fan and is connected thereto by an angularly disposed tube or pipe 20 which is of greater cross sectional area than the coupling collar 16 on the remaining hoppers.

The communication between the bottoms 10 of the hopper and the conveyor pipe may be uncontrolled. However if desired a pivotally mounted door 21, adjustable and actuatable from the exterior of the collar 16 may be provided for controlling the ports 14. In 15 Fig. 3 the door 21 is shown in closed position. It should be noted that when the door is in closed position it extends parallel to and in a plane slightly below the side wall 9 of the hopper and that the port 14 is not 20 entirely closed. Thus there is always at least a small portion of the port 14 remaining open so that material dropping into a hopper may slide over the inclined walls thereof under the influence of gravity and when it reaches 25 the port will be drawn into the suction pipe 15 through which it is conveyed to a suitable separator. One means of controlling the door 21 is conveniently provided by rigidly securing it to a shaft 22 which is journaled in the opposite side walls of the rectangular collar 16. A crank 23 which may extend in parallelism with the plane of the door is secured onto the shaft and may be retained in adjusted positions by means of 30 a screw and thumb nut 24 passing through an arcuately slotted quadrant 25 which is rigidly attached to the side wall of the collar. The pipe 20 connecting the endmost 35 hopper with the end of the suction and conveyor pipe 15 is preferably uncontrolled in all installations in order to provide for a straight unimpeded sweep of the air current throughout the suction and conveyor pipe to the fan 19. It should be noted that the 40 connected transverse edges 12 at the top of adjacent hoppers provide a peak or sharp ridge so that material to be moved has no place 45 upon which to collect.

In Fig. 4 there is shown a top plan view 50 of an extremely long collecting and conveying system. When such a system is required to extend for three or four hundred feet and has many feeder pipes 18 tapped thereinto a plurality of suction and conveyor pipes are 55 provided for controlling sections of the casing 7. In such installations a plurality of fans 19 are used and each is connected by a boot 26 to the side of a suction and conveyor pipe 27 intermediate its ends. In pipe 27 60 opposite each boot 26 a pair of inclined baffles 260 are disposed in spaced parallelism with the walls of the boot to direct material approaching from opposite directions into said boot without conflict. The pipe 27 tapers from the boot to its opposite ends. The 65

casing 7 and hopper structure are as previously described and groups thereof are connected with the several pipes 27. In such installations it is to be understood that all of the fans 19 need not of necessity be operating at one time for efficient performance and that each fan creates a vacuum throughout its allotted length of the casing 7 provided the distribution of the area of branch pipes 18 is approximately uniform throughout the entire length of casing 7. If however the distribution of branch pipes 18 is unequal, part of the air drawn through a given branch pipe 18 may be drawn longitudinally through casing 7 and then downwardly through any of ports 16 70 into any of fans 19, the balance of the air and substantially all of the material being drawn through the port or ports 16 nearest the given branch pipe 18. The several sections of the casing 7, determined by their associated conveyor pipes 27 may be divided or separated from one another by suitable sliding dampers 28 operating transversely through the casing 7. Thus, depending upon the location of waste producing machines in operation, one, two or three of the fans would 75 be set in operation.

In special installations in which the requirements necessitate exceptionally large 80 number and capacity of branch pipes 18, but the use of a fluctuating total number and capacity of said branch pipes, requiring a variable fan capacity; or in the case of an installation of either constant or varying 85 capacity in which the distance from fan or fans 19 to the final destination of materials collected is considerable; it is desirable to provide supplemental fans 30 and connect them with boots 29 to the top or side of casing 7 or to hoppers 8, running a discharge pipe 31 from fan 30 to a dust collector 32 from the top of which collector the air will be dissipated and from the bottom of which collector the material will be dropped into boot 26, or if desirable, directly to the ultimate 90 destination of the fan 19. The addition of fan 30, which may be driven either by constant or variable speed motor device, and may be stopped and started without relation 95 to the constantly operating fans 19, permits of an increase of capacity in the entire casing 7 and the regulation of that capacity in direct proportion to the varying requirements of branch pipes 18.

In Fig. 5 there is shown in elevation one 100 of the supplemental fans 30, connected to the plenum casing 7, and having a variable speed motor 33 equipped with a suitable rheostat or variable controller 34. A pressure regulator 35 of suitable type is mounted in the 105 wall of casing 7 and is adapted to be influenced and actuated by the varying pressures occasioned in the casing by the use of a greater or lesser number or capacity of the 110 branch pipes 18. The regulator 35 may be of 115

the type commonly used on steam boilers with stokers and, since its particular structure forms no particular part of this invention need not be described in detail. It is sufficient to set forth that the varying pressures acting upon the regulator are translated into movement of a rod 36 which connects with switch arm 37 of variable speed control 54 and thus proportionally increases or decreases the speed of the motor and fan. In this way the mere opening of additional branch pipes 18 results in increasing the speed of the motor and fan sufficiently to increase the rate of exhaust of air from casing 7 in proportion to the capacity and requirements of such additional branch pipes. In a like manner the motor or motors 33 are slowed down or completely shut off as the requirements of the total number of branch pipes decrease. In this way the power consumption for the system is kept at a minimum without affecting the uniform efficiency throughout the system.

In Fig. 6 there is shown an installation wherein a constant speed motor 38 drives a mechanical speed regulator 39 connected to a fan such as 30 and provided with an actuating arm 40 for movement by the pressure regulator device. This arrangement likewise provides a uniform pressure within the plenum casing regardless of the number or total capacity of pipes 18 in open communication therewith at any given time.

The operation of the device is as follows: The casing 7 with its associated hoppers and combined suction and conveyor pipe 15 or 27 is installed permanently in a plant and the collars 17 are tapped into the casing 7 at the desired intervals on either side of the casing. The waste producing machines are connected by suitable feeder pipes to the collars, and when the plant is in operation the fan 19 connected with the conveyor pipe and with a suitable separator or arrestor is put in operation. Air is exhausted from the pipe 15 or 27 at a high rate so that the air moves through it at high velocity. The hoppers and casing 7 being in communication with pipe 15 or 27 have the air exhausted therefrom at a lower rate, while the feeder pipes 18, being of relatively small diameter have the air drawn therethrough with sufficient force to convey waste from the waste producing machines (not shown) into the casing 7. In the casing, by reason of the lesser air velocity the waste material immediately drops into the hoppers and to the ports therein, where it is drawn through the relatively small collars 16 into the high velocity stream of air in pipe 15 or 27. The material is carried along in this stream to the fan and separator or arrestor. It should be noted that one suction fan may serve to carry the material from the waste producing machine through the feeder pipes and into the

casing from which the waste material moves into and through pipe 15 or 27 and is conveyed away without the aid of a mechanical conveyor and without entailing the necessity for the use of additional power. The wear on parts and also the noises incident to mechanical conveyors are absolutely eliminated and at the same time power is conserved.

What is claimed is:

1. In a dust collecting system of the class described the combination of a continuous casing from which air is exhausted at a low rate, branch pipes extending from the casing whereby waste material from various sources is carried into said continuous casing, a series of hoppers having discharge ports, the series of hoppers serving to form the bottom of the continuous casing, a conveyor pipe from which air is exhausted at a high rate, said conveyor pipe having constant communication with the discharge ports of the hoppers and means for exhausting air from the conveyor pipe.

2. In a device of the class described the combination of a row of inverted funnel shaped hoppers connected to one another at adjacent top edges thereof, an elongated dome-like casing secured along its edges to the remaining edges of the hoppers, a pipe disposed beneath the bottom of the funnel-like hoppers and communicating with the interior thereof and means for exhausting air at a high rate from said pipe.

3. In a device of the class described the combination of an elongated chamber having its bottom developed into a series of inverted pyramidal funnels, said funnels being truncated to provide discharge ports, collar members on the chamber for connection to feeder pipes, a suction and conveyor pipe extending beneath the discharge ports of the funnels and communicating therewith and means for effecting exhaust of air from said pipe, the exhaust of air serving to carry material through the feeder pipes into the chamber wherein said material falls into the funnels for immediate passage through the discharge ports thereof into the conveyor pipe.

4. In a device of the class described the combination of an elongated chamber casing, a row of truncated pyramidal hoppers forming a bottom for said casing said hoppers having discharge ports therein, a combined suction and conveyor pipe extending beneath and communicating with the discharge ports in the hopper, a suction fan connected to one end of said pipe, an inclined pipe section connecting the end of said pipe with the endmost hopper, said connecting pipe being of a relatively greater cross section than the discharge ports in the remaining hoppers.

5. In a device of the class described the combination of a substantially semi-circular casing member, a series of connected hoppers

- forming a bottom for said casing, the hoppers having inclined side walls, a combined suction and conveyor pipe disposed beneath the hoppers and having communication at spaced intervals with the bottoms of said hoppers, the endmost of said hoppers having a relatively larger area of communication with said pipe than the remaining hoppers of the series. 5
- 10 6. In a device of the class described the combination of a chamber casing having substantially pyramidal communicating hoppers extending from the bottom thereof, a combined suction and conveyor pipe disposed beneath the hoppers, a branch waste collecting pipe connecting with the chamber casing above said hoppers, means providing constant communication between the bottoms of the hoppers and said pipe and means for 15 adjusting the effective area of communication between the hoppers and the pipe. 7. In a device of the class described the combination with a hopper of truncated pyramidal form having a discharge port in the 20 bottom thereof, a pipe extending substantially horizontally beneath said discharge port, an angular collar effecting communication between the discharge port and the pipe and a pivotally mounted door in said collar 25 adjustable from the exterior thereof for altering but not completely closing the effective area of communication between the hopper and the pipe, said door when fully opened being disposed in parallelism with an inner wall of the collar, and being disposed in parallelism with the wall of the hopper when in a closed position. 30
8. The combination of an elongated casing, a series of hoppers forming a bottom 35 for the casing, a plurality of combined suction and conveyor pipes each having communication with different portions of said series of hoppers, individual fans operative upon said pipes and means for cutting off communication between sections of the casing corresponding to the different portions of the series of hoppers. 40
9. The combination of an elongated casing adapted for connection with branch pipes 45 throughout its length, a row of hoppers providing a bottom for the casing, a plurality of independent suction and conveyor pipes aligned beneath the hoppers and connected with different portions of said row of hoppers, means for cutting off communication 50 between sections of the casing corresponding to the several portions of the row of hoppers, individual suction fans for each conveyor pipe and auxiliary fan units connected 55 with the casing and discharging material into the conveyor pipes. 60
10. In combination with a casing having branch pipes operatively communicating therewith in fluctuating numbers and varying 65 total capacities, of a combined suction

and conveyor pipe associated with the casing to exhaust air therefrom and to receive and move material from said casing and means comprising an auxiliary exhaust fan and a pressure regulator connected with the casing whereby fluctuation in total capacity of the operatively connected branch pipes actuates the regulator to vary the rate of exhaust by the auxiliary fan in proportion to the capacity of the branch pipes. 70

11. In combination a casing having branch pipes operatively connected thereto in different total capacities at different times, means for providing air exhaust from the casing for minimum branch pipe capacity 75 and serving to pneumatically convey material delivered to said casing by said branch pipes, and independent auxiliary exhaust means governed by a pressure regulator in the casing for providing additional automatically varying air exhaust from the casing proportionate to the fluctuating total required capacity of the operative branch pipes. 80

In testimony whereof we have hereunto 85 subscribed our names this 14th day of December, 1927.
